CURTAIN TIEBACK DEVICE

Samuel M. Scavetto, Garfield, N. J.

Application February 16, 1956, Serial No. 565,846

5 Claims. (Cl. 24—73)

This invention relates to a device for holding to one side of a wall opening the intermediate or bottom portions of hanging draperies such as curtains.

Conventional curtain tiebacks, used at wall openings such as windows and doors, are ordinarily secured to the frame of the opening by attaching devices such as nails, tacks, thumbtacks, etc. Not only are such devices difficult to locate and drive properly, since usually the housewife wishes the device to be hidden under a fold of the tieback loop, but they mar and deface the frame of the wall opening every time they are driven into the frame. Repeated driving and removal of the devices will so enlarge any one hole in the frame as to necessitate the relocation of the tieback, thus further marring the frame and preventing the re-application of the tieback in the exact location desired.

The curtain tieback device of the invention, which is preferably made as a two-part device, has as one part thereof an attaching bracket adapted to be permanently affixed to a side member of the frame of the wall opening, and as the second curtain-holding part, in the form of a tieback loop or curtain engaging part adapted to be disengageably mounted on the bracket. The two parts of the device are removably held together by a separable snap fastener having its component parts incorporated, respectively, in the bracket and the tieback loop or curtain engaging part. Preferably, the separable fastener is of the type wherein the two parts thereof are engaged and separated by relative movement of the parts in a direction substantially normal or perpendicular to the main extents of such fastener parts. As a result, the tieback loop may be placed in final position relative to the curtain before the second part of the tieback device is engaged with the bracket thereof.

The second part of the tieback device is preferably provided with an outwardly open hook engaging the tieback loop or the curtain itself, and with a flange-like member partially or wholly covering the hook, the supporting member therefor on the second part of the device, the separable fastener parts, and the attaching bracket part of the device. Usually, such flange-like member will be ornamented, to improve the appearance of the tieback device and the curtain arrangement as a whole.

The invention has among its objects the provision of a novel curtain tieback having improved appearance and ease of attachment and disengagement from the frame of a wall opening and a curtain tieback loop on the curtain itself.

The above and further objects of the invention, including economies of use and manufacture will be more readily understood by reference to the accompanying drawing showing a preferred embodiment of the curtain tieback in accordance therewith. In the drawing:

Fig. 1 is an inside front elevation of a window showing curtain tiebacks of the invention in use thereon.

Fig. 2 is an enlarged view in perspective of the parts of the device in exploded relationship, the second, cur-

2

tain tieback loop-engaging part of the device being shown tipped up away from the bracket part thereof.

Fig. 3 is a view in bottom plan of the second part of the device.

Fig. 4 is an enlarged view in horizontal section through the tieback device with the two parts thereof in engagement.

Referring to the drawing, the character 10 generally designates the frame of a window having a curtain composed of curtain halves 14 on the inside of the window. Intermediate their lengths, and somewhat below their vertical centers, each curtain half is pulled outwardly and held by similar tieback devices 15, one on each side of the window frame, engaging tieback loops 16 which extend around the respective curtain halves. The devices 15, to be explained more fully in connection with Figs. 2, 3, and 4, are supported on the left and right hand vertical members 11 and 12, respectively, of the window frame.

Each tieback device 15 consists of a first, L-shaped sheet metal attaching bracket part 17, and a second, tieback curtain loop engaging part 19 adapted to be separably engaged with part 17. Part 17 has a first leg 20 adapted to overlie the inner face of a vertical member of the window frame and a second, shorter leg 21, at a right angle to leg 20, which lies alongside the side surface of such frame member, so as to locate member 17 at the desired distance from the corner of the member and to retain it from turning in a vertical plane about nail or screw 22 which passes through a hole in leg 20 and fastens part 17 to the window frame. Once attached to the window frame, part 17 becomes a permanent part thereof. Leg 20 has attached thereto, as by being soldered at 30, a first metal part 31 of a separable fastener adapted to secure part 19 thereto.

Part 19 of curtain tieback device 15 includes an elongated sheet metal strip body 24 having a generally straight portion 25, on the inner (as regards the window opening) end of which there is attached a bent wire part 26, forming with portion 25 of the strip an outwardly open hook. The base of member 26, which has a sharpened end 27, is secured to strip 24 as by being soldered to the rear face thereof at 29. Beyond the outer end of portion 25, strip 24 is bent so as first to extend into a short straight portion 32 offset rearwardly from portion 25 and thence is curved forwardly to form a substantially closed loop 34.

Portion 32 carries attached to its rear face a second metal part 35, complementary to part 31, of a separable fastener. In the embodiment shown, part 31 is the male part and part 35 is the female part of a known separable fastener of the type known as a "dot" fastener, wherein the two parts are engaged and disengaged by relative movement of the two parts substantially normal to the main extents thereof. Part 35 centrally overlies a hole in strip portion 32 which receives the outer end of stud 36 on fastener part 31.

In use, it is ordinarily preferred to employ tieback loops, such as shown at 16, each of which extends around a curtain half and has its ends impaled on member 26. Tip 27 of such member is spaced sufficiently from fastener part 35 to allow such mounting of the ends of loop 16 thereon. It is then merely necessary, assuming that part 17 of the tieback device has been mounted at the desired location on the window frame, to slide the tieback loop lengthwise of the curtain and then to engage fastener part 35 with part 31 so as to insert stud 36 on the latter into the opening in the former. Part 19 will then be held securely on bracket member 17, and will sustain the sidewise pull thereon exerted by loop 16. When it is desired to remove the tieback, however, a pull inwardly of the room on part 19 will serve to disengage fastener

parts 31 and 35, to free part 19 so that the loop 16 can be removed therefrom and/or from around the curtain half.

For the sake of appearance, and to facilitate manipulation of part 19 of the device, such part is preferably provided with a flange-like member 39 which, in the main, overlies strip 24 so as to hide it, bracket member 17, and the fastener parts 31 and 35 from view. Preferably member 39 lies generally coaxial of fastener part 35, to facilitate engagement of the fastener parts, and has an ornamented face inwardly of the room. Member 39 may be of cementitious material, and may be cast about strip 24 as an insert. Portion 25 of such strip lies generally flush with the outer face of member 39; loop portion 34 of the strip is buried in such member, so that the member and the strip are strongly mechanically interlocked.

It will be apparent that the curtain tieback device of the invention is simple to construct, is rugged in construction, and is easy to install and operate, both to attach the second part of the device to the bracket portion thereof and to disengage it therefrom.

Whereas for purposes of illustration I have shown and described a preferred embodiment of the device, it will be apparent that the device may be varied as to various details as to construction and use within the teaching of the invention. Thus, for example, the member 26 may engage one or more folds of the curtain itself directly, or it may be modified in shape so as to embrace the whole extent of the curtain at its location. Also, in some cases, the device may be used to advantage on a door to which a curtain is attached, or to an arch-way provided with draperies. In such instances the tieback device will be attached, respectively to the frame of the door, and to the wall on the sides of the arch. The expression "frame of an opening" is meant to cover such members as well as the outer frame of a window or door.

The invention is, therefore, to be defined by the scope of the claims appended hereto.

I claim as new the following:

1. A curtain tieback device comprising in combination, an attaching bracket having a flat portion adapted to be secured to the inner face of the frame of a window opening, a member sidewardly elongated toward the opening adapted to be connected to a curtain to be tied back, said member having a first generally flat portion nearest the opening, and a second portion inwardly offset from the first portion and generally parallel thereto, and

a releasable snap fastener on the bracket and member for securing such parts together, said fastener comprising two confronting generally flat parts one of which is a male member having a stud normal to its main extent and the other is a female member receiving the stud, one of the fastener parts being mounted on the second portion of the elongated curtain-holding member.

5. A curtain tieback device as set out in claim 1, in which there is a bent wire member attached to the inner face of the elongated curtain-holding member so as to form therewith a hook open in a direction away from the opening.

10. A curtain tieback device as set forth in claim 2, in which there is a flange-like member connected to the elongated member and overlying the releasable fastener and the elongated member throughout the main extent of the latter.

15. A curtain tieback device as set forth in claim 3, in which the elongated member is continued past the separable fastener into an outwardly bent portion and the flange-like member is of cast cementitious material having the bent portion of the elongated member embedded therein.

20. A curtain tieback device as set forth in claim 3, in which the elongated member is continued past the separable fastener into an outwardly bent portion and the flange-like member is of cast cementitious material having the bent portion of the elongated member embedded therein.

25. A curtain tieback device comprising in combination an attaching bracket having a portion adapted to be secured to the inner face of the frame of a window opening, a member sidewardly elongated toward the opening adapted to be connected to a curtain to be tied back, said member having a first generally flat portion nearest the opening, and a second portion offset toward the frame of the opening from the first portion and generally parallel thereto, and a releasable snap fastener on the bracket and member for securing such parts together, said fastener comprising two confronting parts one of which is a male member having a stud normal to its main extent and the other is a female member receiving the stud, one of the fastener parts being mounted on the second portion of the elongated curtain-holding member and the other being mounted on the attaching bracket.
